UNITED STATES PATENT OFFICE.

ARTHUR A. GERLING, OF NEW YORK, N. Y., AND GEORGE A. L. DU VIGNEAU, OF NORTH BERGEN, NEW JERSEY.

VOICE FOR DOLLS.

Application filed March 4, 1922. Serial No. 541,000.

To all whom it may concern:

Be it known that we, ARTHUR A. GERLING and GEORGE A. L. DU VIGNEAU, residents of New York city, county and State of New York, and North Bergen, Hudson County, State of New Jersey, respectively, and citizens of the United States of America, have invented certain new and useful Improvements in Voices for Dolls, of which the following is a specification.

This invention relates to improvements in sound producing devices for dolls, or in other words, devices for simulating the word mama, or similar sounding words. One of the objects of our invention is to provide a simple inexpensive but effective mechanism to produce sound or a series of sounds to (as has been stated) simulate the word ma-ma.

We will now proceed to describe our invention in detail, the novel features of which we will point out in the appended claims, reference being had to the accompanying drawing, wherein:—

Fig. 1 illustrates our improved device in elevation, the interrupters being indicated in raised position;

Fig. 2 illustrates our improved device partly in elevation and partly in section;

Fig. 3 is a bottom plan view of the device; Fig. 4 is a detail view of the valve; and

Fig. 5 is a fragmentary sectional view illustrating the sound chamber and reed contained therein.

As herein arranged, our improved device comprises a container 7 for a bellows 8, which in this particular case operates longitudinally of the casing to force air through an opening 9 in the head 10 thereof (Fig. 5) and also to draw air through said opening to operate a reed 11 carried by the wall of a chamber 12, said reed being disposed in chamber 12 and opening into a supplemental chamber 13 having an opening 14 which is closed by a valve 15 at intervals.

The valve 15 is carried by an arm 16, pivoted intermediate its ends to a bracket or brackets 17 carried by the head 18 of the supplemental chamber 13. The valve 15 is operated by spaced apart enlargements or projections 20 and 20^a on a rod 21, supported by the movable head 22 of bellows in order that the valve can be operated to close the opening 14 at intervals.

When the device is in use, it will be posi-

tioned so that valve 15 will open or move away from opening 14 by gravity, said valve being made preferably of lead, but not necessarily so. When the casing is tilted so as to cause the bellows to draw in air, the rod 21 will be moved to cause projections 20 and 20^a to be positioned between the tail 19 of the valve-arm 16 and head 10 of the casing as indicated in Fig. 1. When the casing is tilted in the opposite direction, the valve will open by gravity, as indicated in Fig. 1. While the bellows is collapsing, projection 20 will contact with tail 19 of valve arm 16 and close the valve as indicated in Fig. 2, but as the rod 21 will continue to move down, projection 20, will pass the tail piece 19, after which the valve will open. When projection 20^a contacts with tail-member 19, the valve will again close, but as projection 20^a will continue downward, it will, like projection 20, pass tail piece 19, whereupon the valve will again open. While the bellows is opening, air drawn through reed 11 will produce sound, but the valve 15 will interrupt said sound each time it closes; hence, a sound that would be ordinarily continuous will be divided into two sounds, simulating ma-ma. The opposite end of the casing is provided with a partition 7^a which acts as a guide for the rod 21 and which is provided with an opening 7^b through which the air escapes that is acted upon by head 22. The end of the casing is closed with a preferably perforated cap 7^c.

There will be enough side play in rod 21 to permit the projections 20, 20^a to pass tail-piece 19. If desirable the tail-piece 19 may be made yieldable or resilient so that it will give slightly to allow the projections to pass.

When the device is placed in the body of a doll it may be put in, in reversed position to that shown in the drawing, the operation being the same.

What we desire to secure by Letters Patent is:—

1. In a sound producing device, a reed, a bellows to force air through said reed and having a movable member, an air chamber containing the reed having an opening, a valve to close said opening arranged to open by gravity, a tail piece on said valve, a rod carried by the movable member of the bellows, and projections carried by one end of the rod to successively engage said tail

piece to close said valve at intervals during the passage of air through said reed, said projections being spaced one from the other.

2. In a sound producing device, a reed, a bellows to force air therethrough, said bellows having a movable member, an air chamber containing the reed having an opening, an arm pivotally mounted adjacent said chamber, a valve at one end of the arm to close said opening, said valve being arranged to open by gravity, the opposite end of said arm being yieldable, and means operable by the movable member of the bellows to contact with the yieldable portion of the arm to close said valve at intervals during the passage of air through said reed.
3. In a sound producing device, a reed, a

bellows to force air therethrough, said bellows having a movable member, an air chamber containing the reed having an opening, 20 an arm pivotally mounted adjacent said chamber, a valve at one end of the arm to close said opening, said valve being arranged to open by gravity, the opposite end of said arm being yieldable, a rod carried 25 by the movable member of the bellows, and spaced apart projections carried by the rod arranged to contact with the yieldable end of the valve arm to close said valve at intervals during the passage of air through 30 said reed.
